UNITED STATES PATENT OFFICE.

PETER J. KILLEEN, JR., AND PATRICK H. BIRMINGHAM, OF HARTFORD, CONNECTICUT.

SPINNING-DIE.

SPECIFICATION forming part of Letters Patent No. 465,578, dated December 22, 1891.

Application filed May 22, 1891. Serial No. 393,680. (No model.)

To all whom it may concern:

Be it known that we, PETER J. KILLEEN, JR., a citizen of the United States, residing at Hartford, in the county of Hartford and State 5 of Connecticut, and PATRICK H. BIRMINGHAM, a citizen of the United States, residing at Hartford, in the county of Hartford and State of Connecticut, have invented certain new and useful Improvements in Spinning-Dice, of 10 which the following is a specification.

This invention relates to improvements in the dies or "dice" used for determining questions by chance, the object being to provide a die adapted for use by "spinning" instead 15 of by shaking in a dice-box, as hereinafter more fully set forth.

In the drawings accompanying and forming a part of this specification, Figure 1 is a plan 20 view of our improved spinning-die. Fig. 2 is a plan view of the under side of the die. Fig. 3 is a side elevation of the same. Fig. 4 is a central sectional view of the die. Fig. 5 is a side elevation of the die, it being shown lying on one of its sides. Figs. 6 to 20, inclusive, 25 are diagrammatic views illustrative of the various uses of the die.

Our improved spinning-die consists of a central shaft or stem 2, sharpened or pointed at the lower end thereof, as at 3, after the manner of a "spinning-top," an upper flange or disk F, which we denominate the "running-rim," and which is concentric to the axis of rotation of the die, and a solid part or body, as 5, having the depending sides 6, 7, 8, and 9. 35 The lower edges of said sides or faces 6, 7, 8, and 9 constitute a polygonal flange or rim, which we denominate the "stop-rim," and designate in a general way by the letter N, and which consists of the several edges 6', 7', 8', 40 and 9', respectively. The solid part or body C, together with the depending sides thereof, constitute the "body" of the die, also called the "top-body," from its resemblance to the body of a spinning-top.

45 In using the die the player takes it in hand by the stem 2 and spins it on the stem-point 3 thereof in the well-known manner of spinning a top. When the die, owing to the expending of its momentum, nears the end of 50 its spinning, it leans over toward one side, the lower stop-rim of the die strikes the table or

board on which said die is spinning, thus quickly checking the spinning, and the die falls over and runs about on the running-rim 4 and the said stop-rim N until finally the die 55 stops on one of said rim-edges, as illustrated in Fig. 5. The stop-rim N being polygonal, and also extending below the plane of the center of gravity of the die, (indicated approximately by the line e e, Fig. 4,) there is great 60 uncertainty as to the position in which the die will come to rest.

For the purpose of adapting our newly-invented spinning-die for use in various kinds of amusements, we make it with a suitable "interrogatory" and with some answers thereto. In some cases the interrogatory is understood from the die itself, and hence is not expressed thereon.

The interrogatory when expressed is preferably placed on the top of the die, as in Figs. 1, 10, 15, and 20, while on the several facets of the die are a series of answers corresponding to the interrogatory. The character of the answers and their mode of expression 75 should, of course, depend upon the particular amusement or game for which the die is to be used. For instance, for amusement during seasons of political activity, where opposing candidates are nominated for election to a public office the interrogatory may consist of the words, "Who is elected?" or "Which wins?" and the answers on the die-facets consist of the proper names, initials, or "nicknames," or the portraits or other indicative representations 85 of the candidates. There being usually opposing candidates in nomination, we place the indicative representations referring to the respective nominees alternately on the successive facets to thereby increase the uncertainty 90 of the answer, and thus increase the interest of the users of the toy. This use of our spinning-die is illustrated by Figs. 6 to 10, inclusive, the interrogatory, "Who is elected?" being expressed and placed on the top of the die 95 shown in plan view in Fig. 10, while the several candidates are appropriately designated on the respective facets 6, 7, 8, and 9 shown in Figs. 6 to 9, respectively. On spinning the die the name uppermost when the die comes 100 to rest is supposed to be "elected." In the case illustrated the nominees, "Sam Brown"

and "Tom Jones," are supposed to be of one party, while "John Smith" and "Dick Small" are of the opposing party. By this plan the answers are not only "opposing" answers, but are also placed in "alternating succession" on the facets of the die.

For use in playing games with cards the several answers are made appropriate to the particular game in which the die is to be used.

- 5 10 In Figs. 11 to 14, inclusive, the characters P, N, T, and A are placed on the several facets 6, 7, 8, and 9, respectively, and are indicative of "Put in one," "None," "Take one," and "All won," these being the directions (in the 15 form of answers to the query, "Which wins?" in the plan view, Fig. 15) to the successive players, as indicated by the turning of the die. For instance, suppose four players to be playing and each to have six cards, the balance of 20 the pack being on the table. The game being started by each player drawing one from his "hand" and putting it into the "pile," the die is spun by the first player, and stops, let us suppose, at P, indicating "Put in one." 25 Thereupon the first player takes one from his hand and puts it into the pile. The second player next spins the die, which, let us suppose, stops at N, which indicates "None," indicating that the play is a "blank." The 30 third player next spins the die, which, if it stops at T, indicates "Take one," whereupon he draws one card from the pile and puts it into his own hand. Next, the fourth player spins the die, which we will suppose 35 stops at A, indicating "All won," thus entitling the player to take the pile into his own hand. After this more cards may be dealt out from the pack to each player, or the game proceed by other ways.
- 40 40 For playing whist, we make the spinning-die with the interrogatory (expressed or understood) "What is the trump?" (see Fig. 20,) and on the die-facets 6, 7, 8, and 9 place the several possible answers "Spades," "Clubs," "Hearts," and "Diamonds," respectively, each suitably named or symbolized. This 45 may be done as illustrated, for instance, in Figs. 16 to 19, inclusive, where the several

kinds of cards are designated by their indicative figure; or the names of the cards 50 "Spades," "Clubs," "Hearts," and "Diamonds" may be placed on the several die-facets, respectively, instead of the figures aforesaid. In the drawings, the black figures "spades" and "clubs," designated by 10 and 55 12, are placed in alternating succession with the red figures "hearts" and "diamonds," which are designated by 14 and 16, respectively.

The manner of playing whist by the aid of 60 our spinning-die is or may be as follows: All of the cards being dealt out, as usual, but without determining the trump, one of the players spins the die, and the side stopping uppermost is taken to indicate the trump. 65 In practice, the spinning of the die for one "play" may be done by the player who dealt at the next previous play; or, the one about to deal may spin the die, as may be agreed by the players.

Having thus described our invention, we claim—

1. In a spinning-die, the combination, with the top body and stem, of the circular running-rim above the plane of the center of gravity of the die, and the polygonal stop-rim at the lower end of said body, substantially as described.
2. In a spinning-die, the combination, with the top-body having a series of die-facets 80 adapted to receive characters, of a circular running-rim above said facets and concentric to the axis of rotation of the die, substantially as described.

3. In a spinning-die, the combination, with 85 the top-body and the stem-point, of the running-rim above the center of gravity of the die, and having the die-facets depending below the said body to form a polygonal stop-rim, substantially as described.

PETER J. KILLEEN, JR.
